UNITED STATES PATENT OFFICE.

WILLIAM B. STOUT, OF DETROIT, MICHIGAN, ASSIGNOR TO PACKARD MOTOR CAR COMPANY, OF DETROIT, MICHIGAN, A CORPORATION OF MICHIGAN.

AIRPLANE.

Application filed March 2, 1918. Serial No. 220,070.

To all whom it may concern:

Be it known that I, WILLIAM B. STOUT, a citizen of the United States, and residing at Detroit, Wayne County, State of Michigan, have invented certain new and useful Improvements in Airplanes, of which the following is a specification.

The present invention relates to airplanes and more particularly to the wings thereof.

10 The principal objects of the invention are to provide an exceedingly simple and dependable means for varying the camber of the wings; to provide a rib structure which can be manufactured with a minimum of 15 time and labor and which has maximum strength for a given weight; and to provide a rib having a bendable member adapted to be flexed to vary the camber thereof. Other objects and features of the invention will 20 be apparent from the description taken in connection with the drawings, in which:

Figure 1 is a plan view of an airplane showing the fuselage and a pair of wings, a portion of the upper surfaces of the latter 25 being broken away to illustrate the connections for changing the camber thereof;

Figure 2 is a perspective view of a rib for the wing and showing the means for changing the camber of one of its members;

30 Figure 3 is a perspective view of a metal rib having a bendable strip attached to the lower member thereof and showing the means for flexing this latter member to change the camber of the rib;

35 Figure 4 is a perspective view similar to Figure 3 showing a similar form of rib but with the upper member thereof provided with a bendable strip;

40 Figure 5 is a perspective view of a detail illustrating the means for changing the camber;

Figure 6 is a sectional elevation taken substantially on the line 6—6 of Figure 3;

45 Figure 7 is a sectional elevation taken substantially on the line 7—7 of Figure 4;

Figure 8 is a sectional elevation taken substantially on the line 8—8 of Figure 4;

50 Figure 9 is a side elevation of a rib similar to that shown by Figure 3 except that the bendable strip is supported at three points and extends substantially from end to end of the rib;

Figure 10 is a side elevation of a stamped or pressed out metal rib;

55 Figure 11 is a sectional elevation taken

substantially on the line 11—11 of Figure 10, and

Figure 12 is a diagrammatic elevation illustrating a means for connecting the camber changing mechanisms of the planes so 60 that they are operated simultaneously.

Referring to Figure 2 of the drawings a rib for airplane wings is shown which comprises the upper longitudinal member 20 which is convexly curved and the lower 65 longitudinal member 21. These two members may be integral, the rib being formed by bending a single strip to the outline illustrated or it may be made in other ways. At its front end or nose the rib has its two members connected or reinforced by the angle piece 23 and at its rear end the two members are connected in any suitable manner as by means of the pin 24 and clip 25. Adjacent 70 the nose, one of the members, as the upper 75 member, has secured thereto a bracket 26 through which extends the tubular spar 27 formed with the aperture 28 through its wall adjacent the said bracket. A tube 29 is rotatively mounted within the spar and has an arm 30 extending radially through the aperture 28, the outer end of which is connected by means of a link 31 to a bracket or fitting 32 secured to the lower member of the rib. This lower member is formed so 80 that it can be flexed to change the camber of the rib and it will be apparent that rotation of the sleeve 29 through the arm 30 and link 31 will vary the curvature of the said bottom member. The construction of rib just 85 described is particularly adapted for use in multi-plane air ships in which, because of the plurality of planes, the length of each plane from nose to tail is relatively small. In other words, the length of rib required 90 for this type of plane is relatively short and consequently does not need to be of as rigid a construction as is necessary in planes having longer ribs.

In Figures 10 and 11 I have shown a novel 100 form of rib or beam which is designed to be stamped or pressed out from sheet metal. As illustrated, this rib is of channel cross-section and comprises the top member or flange 33 and the bottom member or flange 105 34 connected by the web 35. This web is formed with the flanged apertures 36, the flanges 37 of which are interposed between and lie substantially in the plane determined by the top and bottom flanges and constitute 110

reinforcing members or rings. As shown, these reinforcing members or rings are in contact with the flanges and with one another. In order to increase the rigidity and strength of the beam the parts are secured together at these points of contact in any suitable manner as by welding. Of course the top and bottom members and the entire beam are constructed to give the proper camber to the rib. As is obvious, a rib or beam constructed in this manner is exceedingly strong and rigid for the amount of material or weight used.

In Figures 3, 4, 6, 7 and 8 I have shown a rib of the type just described, but with the added feature of means for changing the camber thereof. Referring now to Figure 3, it will be seen that the rib proper is of channel shape in cross section and is intended to be formed by being stamped or pressed out from sheet metal. It comprises the top flange or member 38 and the bottom member 39, connected by the web 40, which is formed with the flanged apertures 41. These latter flanges 41' constitute reinforcing members or rings and are interposed between the top and bottom members and welded thereto and to each other. As clearly shown in Figure 3, the front portion of the lower member 39 is offset toward the top member 38, thus forming a recess. At the ends of this recess, socket pieces 42 and 43 are provided and a bendable strip 44 is arranged with its ends mounted in said sockets. The forward end of the strip is secured in the socket 43 by means such as a pin 45 while the rear end is free to slide longitudinally in the socket 42. The rib is carried by a tubular spar 27 which extends through the same between the top and bottom members and which is formed with an aperture 28 through which extends a radial arm 30 carried by a tube 29 rotatively mounted in the spar. As shown, the spar is mounted in one of the apertures 41, being secured to the flange 41' in any suitable manner. The strip 44 carries a bracket or fitting 32 and a link 31 operatively connects the said bracket and the arm 30 so that rotation of the tube 29 varies the curvature of the strip 44 thereby changing the camber of the rib.

Figure 4 illustrates a construction similar to that shown by Figure 3 except that the bendable strip is carried by the upper member of the rib. In this form of the invention the channel shaped stamped metal rib has its upper member 46 offset towards the lower member 46' to thereby form a recess. At the ends of this recess the rib is formed with socket pieces 47 and 48 and a bendable strip 49 is mounted with its end seated in the said socket pieces, one end as the front end being secured by a pin 48', the other end being

free to slide in the socket 47. This strip intermediate its ends carries a bracket 32 and is adapted to be flexed in the same manner as described in connection with Figure 3.

As shown in Figure 6 the socket 42 may be formed by bending up an extension on the lower flange 39 and the socket 47 may be formed in a similar manner, as shown in Figure 7. Likewise the sockets 43 and 48 may be formed by bending up a piece integral with the rib as illustrated in Figure 8.

In Figure 9 I have illustrated a stamped metal rib having one of its flanges offset towards the other for the greater part of its length to form a recess in which is arranged a bendable strip supported at three points. Although the bendable strip may be attached to either the top or bottom member, I have shown only the latter form. The lower member 50 of the rib is offset towards the upper member 51, as shown, and adjacent the nose of the rib there is provided the socket piece 52, and at the tail end the socket 53. Midway between these two sockets is a support 54. The bendable strip 55 is mounted in these sockets and support, being held securely in the support 54 by a pin 56, but free to slide in the sockets 52 and 53. For the purpose of changing the camber of the rib I have shown the bracket 32 attached to the strip 55 at a point intermediate the socket 52 and support 54. This bracket 32 is the same as that already described and is adapted to be moved towards and from the rib by any suitable mechanism, preferably the same as described in connection with Figures 2, 3 and 4. It will be observed that the movement of the bracket 32 will flex the strip 55 between the socket 52 and support 54 and will also cause an opposite curvature of the portion of the bracket between the support 54 and socket 53. The sockets 52 and 53 and support 54 may be formed in the same manner as the sockets 110 described above. These ribs without the camber changing feature are claimed in application 459,641, a division of this application.

It is apparent that the connection between the rotatably mounted tube 29 and the bendable member of the rib may be made in various ways. As shown in Figures 2, 3 and 4 and to a larger scale in Figure 5, the arm 30 may be struck up from the wall of the tube 29. For this purpose the arm is formed before assembling the parts and afterwards it is bent out through the aperture 28 to a position at right angles to the tube. The aperture 28 in the spar is of such dimensions that it permits the arm to be bent up and also allows the necessary angular movement of the same in the operation of the plane.

As shown in Figure 1, the rotatable tubes

29 of a pair of wings 56 and 57 extend into the fuselage 58 and at their adjacent ends may be provided with any suitable operating means as the levers 59. The rotatable tubes 5 29 of the other planes of the aircraft may be operated as shown in Figure 12. Thus each of the tubes 29 may be provided with a crank arm 60, and these arms connected by a link 61.

10 From the foregoing description it is apparent that I have provided an exceedingly simple and dependable means for varying the camber of the wings of an airplane. The connections are all positive, there being no 15 pulleys or wires. Furthermore, a very few parts are used, all of which are adapted for manufacture according to the principles of standardization, and a minimum of fitting is required in assembling the planes. The 20 ribs are also especially adapted for quantity and standardized production. The metal rib in particular can be manufactured by automatic machinery, there being a minimum of hand labor required. Furthermore, a rib, 25 made according to the present invention, of sheet metal and stamped out, can be produced in a fraction of the time required for the old style wooden rib. The tedious time-consuming steps of selecting and bending the 30 wood, shaping the parts, gluing, etc. are entirely eliminated; also the period of a year or more required to season the wood.

It is apparent that the details of the constructions described may be varied without departing from the spirit of the invention.

I claim:

1. A wing for airplanes including in combination, a rib having a member constructed and arranged to be flexed, a single spar supporting said rib and having means operative on said member to flex the same to vary the camber of the wing.

2. In an airplane wing, the combination with a rib having top and bottom members, 45 of a spar supporting said rib, and means for changing the curvature of one of said members including an element carried by said spar and mounted for rotative adjustment about an axis extending transversely of said 50 rib.

3. A metal rib for airplanes comprising longitudinal top and bottom members, one of said members adjacent the nose of the rib being offset toward the other thereby forming a recess, and a bendable strip arranged in said recess.

4. A metal rib for airplanes comprising longitudinal top and bottom members, one of said members adjacent the nose of the 60 rib being offset toward the other thereby forming a recess, and a bendable strip arranged in said recess and secured at its ends to said member.

5. A rib for the wing of airplanes comprising a member convexly curved longi-

tudinally, a lower member slightly curved longitudinally, one of said members having a portion offset toward the other member to form a recess and a bendable strip in said recess having its ends secured to the rib. 70

6. A rib for the wing of airplanes comprising an upper member convexly curved longitudinally, a lower member slightly curved longitudinally, one of said members having a socket intermediate its ends and a 75 second socket adjacent the nose of the rib, and a bendable strip having its ends mounted in said sockets.

7. An airplane wing including in combination a metal rib comprising top and bottom members, a spar extending through the rib between said members, a bendable strip carried by one of said members adjacent the nose of the rib, and means carried by said spar operative on said strip to flex the same. 80

8. A rib for airplanes comprising top and bottom members, means connecting said members, one of said members having a portion offset toward the other member, thereby forming a recess, and a bendable strip arranged in said recess. 85

9. An airplane wing including a rib comprising top and bottom members, means rigidly connecting said members, one of said members having a portion offset toward the 95 other, thereby forming a recess, a bendable strip arranged in said recess, and means to flex said strip.

10. An airplane wing including a rib comprising top and bottom members, means rigidly connecting said members, one of said members having a portion offset toward the other, thereby forming a recess, a bendable strip arranged in said recess, and means carried by the rib to flex said strip. 100

11. An airplane wing including a rib comprising top and bottom members, means rigidly connecting said members, one of said members having a portion offset toward the other, thereby forming a recess, a bendable 110 strip arranged in said recess, a spar extending transversely of said rib, and means carried by said spar to flex said strip.

12. A metal airplane rib comprising a single strip of sheet metal having longitudinally curved top and bottom members formed by bending up the upper and lower edge portions of the blank, and an intermediate web portion having struts and inter-strut openings, one of said members having 120 a portion offset toward the other forming a recess, and a bendable strip arranged in said recess.

13. A stamped metal airplane rib comprising an integral structure including longitudinally curved top and bottom members and arch-shaped struts connecting said members, one of said members having a portion offset toward the other forming a recess, and a 125 bendable strip arranged in said recess. 130

14. A stamped metal airplane rib including longitudinally curved top and bottom members and struts connecting said members, one of said members having a portion offset toward the other forming a recess, and a bendable strip arranged in said recess.
15. As an article of manufacture, an airplane rib made from sheet material, comprising a web, longitudinal marginal flanges struck up at an angle thereto, reinforcing members struck up from the web and interposed between and welded to said flanges, a portion of one of said flanges being offset toward the other forming a recess, and a bendable strip arranged in said recess.
16. As an article of manufacture, an airplane rib made from sheet material, comprising a web, longitudinal marginal flanges struck up at an angle thereto, and arch-shaped reinforcing members struck up from the web and interposed between said flanges, a portion of one of said flanges being offset toward the other forming a recess, and a bendable strip arranged in said recess.
17. As an article of manufacture, an airplane rib made from sheet material, comprising a web, longitudinal marginal flanges struck up at an angle thereto and circular reinforcing members struck up from the web and interposed between said flanges, one of said flanges having a portion offset toward the other forming a recess, and a bendable strip arranged in said recess.
18. As an article of manufacture, an airplane rib made from sheet material, comprising a web, longitudinal marginal flanges struck up at an angle thereto and reinforcing members struck up from the web and interposed between said flanges, one of said flanges having a portion offset toward the other forming a recess, and a bendable strip arranged in said recess.
19. As an article of manufacture, a metal beam of channel section having a series of circular reinforcing members secured to the web and interposed between and secured to the flanges thereof, one of said flanges having a portion thereof offset toward the other forming a recess, and a bendable strip arranged in said recess.
20. As an article of manufacture, a flanged sheet metal beam of channel section having a series of circular reinforcing members struck up from the web and interposed between the flanges thereof and welded to each other and the flanges, one of said flanges having a portion thereof offset toward the other forming a recess, and a bendable strip arranged in said recess.
21. As an article of manufacture, a flanged sheet metal beam of channel section having reinforcing members struck up from the web interposed between and welded to the flanges thereof, one of said flanges having a portion thereof offset toward the other form-
- ing a recess, and a bendable strip arranged in said recess.
22. As an article of manufacture, a flanged sheet metal beam of channel section having reinforcing members interposed between and welded to the flanges thereof, one of said flanges having a portion thereof offset toward the other forming a recess, and a bendable strip arranged in said recess.
23. As an article of manufacture, a metal beam of channel cross section having a web and top and bottom flanges, the web being formed with a plurality of flanged apertures, the latter flanges interposed between and acting to reinforce the said top and bottom flanges and stiffen the web, one of the top and bottom flanges having a portion thereof offset toward the other forming a recess, and a bendable strip arranged in said recess.
24. A metal rib for airplanes comprising a web having a flange at the top and bottom edges thereof, reinforcing members interposed between and welded to said flanges, one of said flanges having a portion thereof offset toward the other forming a recess, and a bendable strip arranged in said recess.
25. A metal rib for airplanes comprising a web having a flange at the top and bottom edges thereof constituting top and bottom members, said member formed with circular flanged apertures, the latter flanges being interposed between and welded to said members and acting to reinforce the same and stiffen the web, one of said members having a portion offset toward the other forming a recess, and a bendable strip arranged in said recess.
26. A metal rib for airplanes comprising top and bottom members and reinforcing rings interposed between, joined to and arranged in the plane determined by, said members, and also joined to each other, one of said members having a portion thereof offset toward the other forming a recess, and a bendable strip arranged in said recess.
27. A metal rib for airplanes comprising top and bottom members and reinforcing rings interposed between, integrally joined to and arranged in the plane determined by, said members, one of said members having a portion thereof offset toward the other forming a recess, and a bendable strip arranged in said recess.
28. A rib for airplanes comprising top and bottom members, means connecting said members, one of said members having a portion offset toward the other member, thereby forming a recess, and a camber changing device arranged in said recess.
29. A rib for the wing of airplanes comprising an upper member convexly curved longitudinally, a lower member slightly curved longitudinally, one of said members having portions bent to form spaced sockets

and a bendable strip supported in said sockets.

30. A rib for the wing of airplanes comprising an upper member convexly curved longitudinally, a lower member slightly curved longitudinally, one of said members having portions bent to form sockets, one of said sockets being adjacent the nose of the rib and the other at a point intermediate the ends thereof, and a bendable strip supported in said sockets.

31. A metal rib for airplanes comprising top and bottom members, one of said members having a socket adjacent the nose of the rib and a second socket spaced therefrom along the length of the rib and a bendable strip supported at its ends in said sockets.

32. In an airplane, in combination, a rib, a hollow rotatively mounted shaft having an arm struck up therefrom, and means connected to said arm to vary the camber of said rib when said shaft is rotated.

33. In an airplane, in combination, a rib, a tubular spar formed with an opening in its wall, a shaft rotatively mounted in said spar, an arm rigid with said shaft projecting through said opening, and means connected to said arm to vary the camber of said rib when said shaft is rotated.

34. In an airplane, in combination, a rib, a tubular spar formed with an opening in its wall, a hollow shaft rotatively mounted

in said spar, an arm struck up from said shaft projecting through said opening, and means connected to said arm to vary the camber of said rib when said shaft is rotated.

35. In an airplane, in combination, a tubular spar formed with an opening in its wall, a shaft rotatively mounted in said spar, an arm rigid with said shaft projecting through said opening, a rib constructed to have its camber changed, and a link connected to said arm and operative on said rib to vary its camber when said shaft is rotated.

36. In an airplane, in combination, a hollow spar having an opening through its wall, a shaft rotatably mounted in said spar, a rib carried by said spar, and means extending through said opening operatively connecting said shaft and said rib to vary the camber of the rib when the shaft is rotated.

37. In an airplane wing, the combination with a rib having top and bottom members, of a spar constituting the main support for said rib, and means to vary the curvature of one of said members including a rotatively mounted element extending transversely of the rib and carried by said spar.

In testimony whereof I affix my signature.

WILLIAM B. STOUT.
